UNITED STATES PATENT OFFICE.

VICTOR FRANK VON LOSSBERG, OF NEW YORK, N. Y.

DESIGN FOR A CHANDELIER.

53,186.

Specification for Design.

Patented Apr. 8, 1919.

Application filed January 4, 1918. Serial No. 269,697. Term of patent 3½ years.

To all whom it may concern:

Be it known that I, VICTOR FRANK VON LOSSBERG, a citizen of the United States of America, and residing in the city, county, and State of New York, have invented a new, original, and ornamental Design for a Chandelier, of which the following is a specification, reference being had to the accompanying drawing, forming part thereof.

The figure constitutes a front elevation of a chandelier embodying my invention.

The shape of the candles and candle lamps may be varied, those shown being illustrated merely by way of example and do not enter into the design of the chandelier proper. The pendant ornaments are preferably made of cut glass.

What I claim is:

The ornamental design for a chandelier substantially as shown and described.

VICTOR FRANK VON LOSSBERG.
